UNITED STATES PATENT OFFICE.

SIDNEY MASON, OF PHILADELPHIA, PENNSYLVANIA, ASSIGNOR TO
WELSBACH LIGHT COMPANY, OF GLOUCESTER CITY, NEW JER-
SEY, A CORPORATION OF NEW JERSEY.

INCANDESCENT GAS-LIGHT.

No. 817,081.

Specification of Letters Patent.

Patented April 3, 1906.

Application filed December 8, 1905. Serial No. 290,879.

To all whom it may concern:

Be it known that I, SIDNEY MASON, of Philadelphia, in the county of Philadelphia and State of Pennsylvania, have invented a new and useful Improvement in Incandescent Gas-Lights, of which the following is a specification, reference being had to the accompanying drawings, forming part of this specification, in which—

10 Figure 1 is a side elevation of my improved globe with the incandescent lighting-mantle therein, the latter being shown in dotted lines. Fig. 2 is a cross-section through the globe, and Fig. 3 is a section on the line 15 III III of Fig. 1.

The purpose of my invention is to provide novel and efficient means for utilizing incandescent gas-lighting mantles in inverted positions. Mantles designed for this purpose 20 are generally of approximately semiglobular form and are set on the burner in such manner that the gas - flame is directed downwardly therein. To use such mantles efficiently, the air must be supplied in an even 25 manner, for if currents of air should strike the mantles in greater volume at one point than another it will produce a defective and irregular flame. It has been attempted to obtain this result by the use of a glass globe 30 having perforations at the sides and made of substantially uniform diameter from top to bottom or of somewhat greater diameter at the bottom, where the perforations are situated, than at the top; but such globes have 35 not produced satisfactory results, for the air entering the lateral perforations impinges upon the mantle unevenly and produces an irregular flame. It has also been attempted to accomplish the result by using a globe having 40 a central opening at the bottom; but while this will supply the air in a regular stream it involves danger in the use of the light, because such mantles sometimes accumulate carbon, which, becoming incandescent, will drop through the bottom opening, causing liability of fire in the building. For 45 this reason such globes are not approved by the insurance companies.

My invention overcomes the difficulties 50 above mentioned and provides a safe light in which the air is supplied uniformly and the

best and the most satisfactory operation of the mantle is secured.

The invention consists in the combination, with an inverted incandescent mantle, of a globe in which the same is contained, said globe having below the mantle a constricted central passage and below said constricted passage having lateral perforations through which the external air is admitted. 55

In the drawings, 2 represents the incandescent mantle set in inverted position within the globe 3. This globe has below the mantle a constricted central passage 4, and below this passage is a chamber 5, having lateral 60 openings 6, through which the external air is admitted and from which it passes upwardly through the constricted portion 4 to the mantle. The entire globe, including the parts 3 and 5, is made of glass in a single 65 piece, and if any incandescent carbonized material should drop from the mantle it will be caught in the base of the portion 5 and will be prevented from dropping on the floor. 70

Within the scope of my invention the form 75 and design of the parts may be changed in many ways, since

What I claim is—

1. A glass globe for inverted incandescent mantles having in the lower part of the body 80 portion a constricted central passage of smaller diameter than the body, and opening into a lower chamber having lateral air-openings.

2. A glass globe for inverted incandescent 85 mantles having at its lower end a chamber with a closed bottom and lateral air-openings, said chamber communicating with the body of the globe through a constricted central air-passage. 90

3. A glass globe for inverted incandescent mantles provided at its lower end with a chamber having a closed bottom and air-openings in its side portions, said chamber connecting with the globe-body through a 95 constricted central air-passage.

In testimony whereof I have hereunto set my hand.

SIDNEY MASON.
